UNITED STATES PATENT OFFICE.

CHARLES F. BROWN AND WILLIAM T. LOWRY, OF CHATTANOOGA, TENNESSEE,
ASSIGNORS TO CLARENCE S. STEWARD, OF CHATTANOOGA, TENNESSEE.

ELECTRIC HEATER.

1,099,786.

Specification of Letters Patent.

Patented June 9, 1914.

Application filed April 8, 1914. Serial No. 829,257.

To all whom it may concern:

Be it known that we, CHARLES F. BROWN and WILLIAM T. LOWRY, citizens of the United States, residing at Chattanooga, in the county of Hamilton and State of Tennessee, have invented certain new and useful Improvements in Electric Heaters; and we do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in electric heaters adapted to contain two different circuits and so arranged that heat may be obtained in either one or the other of the same.

More specifically, the present invention comprises a heater made of steatite or other suitable material in which channels are formed for the reception of the circuit wires and which are kept separate from one another and in which the entire wiring is accomplished above the bottom portion of the plate and which is smooth and imperforate except at the terminal post.

Our invention comprises various other details of construction, combinations and arrangements of parts which will be herein-after fully described, shown in the accompanying drawings and then specifically defined in the appended claim.

We illustrate our invention in the accompanying drawings, in which:

Figure 1 is a top plan view of a plate of steatite or other suitable material and in which grooves are formed for the reception of two independent wirings adapted for separate circuits. Fig. 2 is an edge view of the plate shown in Fig. 1. Fig. 3 is a sectional view on line 3-3 of Fig. 1. Fig. 4 is a top plan view of a slight modification of our invention. Fig. 5 is an edge view of Fig. 4, and Fig. 6 is a section on line 6-6 of Fig. 1.

Reference now being had to the details of the drawings by letter, A designates a plate of steatite or other suitable material which may be found to be well adapted for the purpose and which is provided with series of slots B running parallel to each other and formed in the upper face of the plate, the

bottom of the plate being imperforate and without slots, merely having holes C formed therein for the terminal screws D, D', D² and D³ to which the ends of the wiring are connected. Said slots have oppositely disposed enlarged or chambered portions E and F, the upper series of chambers E being adapted to receive the wiring H, while the lower series contains the wires K. One end of the wire K is connected to the terminal screw D, as shown clearly in Fig. 1 of the drawings, and passes through a channel or duct N intermediate the first and second slots, as shown clearly in Fig. 2, running back the length of the second channel and through a passageway or duct O and back through the third parallel slot B, thence through a duct Q connecting the ends of the third and fourth slots and so on back and forth across the entire surface of the plate. The wiring H has one end fastened to the terminal screw D' and passes in a zig-zag relation through the chambers E, the wiring passing through channels or ducts, designated by letter L, formed in the partitions intermediate the slots and connecting the chambered portions E at the ends of the plate.

In Fig. 2 of the drawings, we have shown the wiring H passing through one of said ducts L and which are formed alternately at the opposite edges of the plate and which extend in a zig-zag relation to the opposite side of the plate where the end of the wire H is fastened to the terminal D². By this arrangement of the wiring, it will be noted that two heating units are provided with the wiring for each circuit disposed over that of the other, the two wirings being kept separate from each other and with an imperforate bottom to the plate, the air to be heated being furnished through the ends of the slots leading to the chambers in which the wire is positioned and affording means whereby one circuit or the other may be utilized accordingly as the heat from one or the other circuit or both together may be desired.

In Figs. 4 to 6 of the drawings, we have shown a modified form of the device in which the plate A' is provided with a series of slots, designated respectively by numerals 1, 2, 3, 4, 5, 6, 7, 8, 9, 10, 11, 12, 13 and 14, each of which is broadened at its lower end forming a chamber A². A wire, design-

2
nated by letter R, is connected to a terminal R' and passes through a chambered portion in the lower portion of the slot 1, thence passes through a duct R² which connects the chambered portion of the slot 1 with the chambered portion of the slot 3. The wire R thence passes through a duct R³ which connects the chambered portions of the slots 3 and 5 at the opposite edge of the plate, and the wire R passing back through the chambered portion of the slot 5 passes through a duct R⁴ which communicates between the chambered portion of the slots 5 and 7, as shown clearly in Fig. 5 of the drawings. Said wire R thence passes back and forth in a zig-zag relation in the same manner and through similar slots and ducts through the other half of the plate and its end fastened to the terminal R⁵. The second wire, designated by letter S, fastened at one end to the terminal S', passes through a portion of the slot 1, back through slot 2, thence down through the duct S³ which passes underneath the slot 3, thence through the slot 4 and through a duct formed between the partitions intermediate the slots 4 and 6, back through the chambered portion of the slot 6 and through a duct R⁶, as shown clearly in Fig. 5, thence up and through a chambered portion of the slot 9, through a duct connecting the slots 9 and 10 and through the latter, thence through a duct R⁷, back through a slot 13, through a duct between the slots 13 and 14 and back to the terminal R⁸. In this modified form, it will be noted that the two wirings are ar-

ranged in alternate relation with each other and each kept separate from the other and held securely in place by the interlocked relation of the wiring with the walls of the chambered portions and the ducts through which the same pass and without forming any perforations in the bottom of the plate. By this arrangement, either one circuit or the other may be utilized as may be desired, according to the degree of heat wished to be produced. By this arrangement of heat units, it will be noted that the heat will be evenly distributed over the entire surface of the plate and the bottom of the latter will be smooth, excepting at the points where the terminals pass through.

What we claim to be new is:

An electric heater comprising a plate having slots formed only in the upper surface thereof, said slots having oppositely disposed chambered portions and two separate wirings mounted one above the other in said chambered portions, the walls between the chambered portions having alternately arranged ducts through which the wirings pass and serving to hold the two wirings separate from each other, and terminals to which the wirings are connected, as set forth.

In testimony whereof we hereunto affix our signatures in presence of two witnesses.

CHARLES F. BROWN.
WILLIAM T. LOWRY.
